CLAIM

The ornamental design for a vehicle body, as shown and described.

DESCRIPTION

FIG. 1 is a front view of a vehicle body showing the new design;

FIG. 2 is a right front view thereof;

FIG. 3 is a right side view thereof, the left side being a mirror image thereof;

FIG. 4 is a left rear view thereof; and,

FIG. 5 is a rear view thereof.

In the photographs, the grille, emblems, wheels, tires, headlamps, windshield wipers, rear view mirrors, tail lamps, hood vents, tail pipes and rear decklid trim element form no part of the claimed design.

The broken lines represent portions of the structure that form no part of the claim.
